ROBERT SPEAR, OF NEW HAVEN, CONNECTICUT. #

Letters Patent No. 97,822, dated December 14, 1869.

IMPROVEMENT IN PNEUMATIC ENGINES.

The Schedule referred to in these Letters Patent and making part of the same.

To all whom it may concern:

Be it known that I, ROBERT SPEAR, of New Haven, in the county of New Haven, and State of Connecticut, have invented certain new and useful Improvements in Mine-Draining Engine; and I do hereby declare that the following is a full, clear, and exact description thereof, reference being had to the accompanying drawings, and to the letters of reference marked thereon, which form a part of this specification.

The nature of my invention consists in the construction and arrangement of a hydraulic engine, to be used for draining mines or other purposes.

In order to enable others skilled in the art to which my invention appertains, to make and use the same, I will now proceed to describe its construction and operation, referring to the annexed drawings, in which—

Figure 1 is a perspective view of the engine, a portion of the cylinder being broken away to show the piston;

Figure 2 is a side elevation; and

Figure 3 is a horizontal section of the same.

A represents the cylinder, made very strong, and capable of sustaining a pressure of several hundred pounds when it is required to raise the water to a great height, or of sufficient strength to correspond with the required elevation of the water, for whatever purpose it may be used.

In the side of the cylinder, near or at its bottom, is a man-hole, B, for the purpose of cleaning the cylinder of any dirt and sediment settling within the same from the water, said man-hole being closed in any suitable manner.

Near the bottom, on one side of the cylinder, is the inducting water-valve C, and on the opposite side, at the same height, is the educting water-valve D, connected with the pipe E, to carry or raise the water to any desired height.

The inducting-valve C is so constructed as to open inward and allow free ingress to the water, but will close to any pressure from the inside, preventing the water from passing out through the same.

The egress-valve D is just the reverse, opening outward, so as to allow the water to be forced through the same.

Within the cylinder A is placed the piston G, which is of such size as to leave a space between its outer circumference and the inner surface of the cylinder, as shown in fig. 3.

The piston G is guided in its motion up and down within the cylinder by means of two ribs or tongues, a a, placed vertically in the sides of the cylinder, and projecting into notches or suitable grooves made for that purpose in the edge of the piston.

The piston-rod H, secured to the centre of the piston G, passes upward through a stuffing-box in the upper head of the cylinder.

In the upper head of the cylinder A are two pipes, I and J, the pipe I being the inducting force-pipe, and J, the exhaust-pipe, both being provided with valves b and d, respectively, and said valves or stop-cocks are connected, by means of a rod, e, so as to be operated simultaneously. They are, however, so arranged that when one is open, the other is closed, and *vice versa*.

To the valve-connecting rod e is attached a vertical rod, f, which passes up through a horizontal plate, K, secured to the pipes I and J, and through which the piston-rod H also passes.

On the opposite side of the piston-rod H from that on which the rod f moves, is placed a standard, L, between the cylinder and the cross-head K.

This standard is provided with a groove, i, vertical in the centre, and curved at both ends, and around each end of said standard is placed a spiral spring, g.

Around the standard L, between the spiral springs g g, is placed a loose collar, h, which moves up and down on the standard, and is guided by a pin or feather on its inside, fitting in the groove i.

From the outside of the collar h projects a pin, m, as seen in fig. 1.

Upon the piston-rod H, at a suitable point, is secured a collar, k, having an arm, n, extending outward toward the standard L, and another arm, o, extending in the opposite direction, that is, toward the rod f, upon which are placed two adjustable collars, p p, at suitable distance apart.

The engine is operated by being placed at the lowest point from which it is desired to elevate the water, and in such a manner that the water can flow around and as high as, or higher than the top of the cylinder, which is filled by the flow of water through the valve C.

The piston G is so constructed that it floats in the water in the cylinder, and is raised as the water flows into it. The piston is guided clear of the cylinder by means of the ribs or tongues, as above mentioned.

The use of the piston is to alternately open and close the stop-cocks b d, in the force and exhaust-pipes I J, and is accomplished in the following manner:

Near the close of the upward stroke of the piston G, the arm n, on its rod H, meets the pin m, on the sliding collar h, which, acting upon the spiral spring above, tends to retard the ascent of the piston and depress it in the water in the cylinder.

The collar h, however, following the curvature at the upper end of the groove i, gradually turns away from the arm n, and becomes, at the proper point, disconnected from the same.

At the same time the short arm o strikes the upper collar p, upon the rod f, which is suddenly elevated by the depressed piston rising in the water.

This action closes the exhaust-valve d and opens the force stop-cock b, allowing the compressed air to pass through the force-pipe I, and act directly with its

full force upon the water, expelling the same through the educting-valve D and pipe E.

At the instant when the pin *m*, upon the slide *h*, becomes disengaged from the arm *n*, as above described, the slide falls down along the standard *L*, following the groove *i*, until it rests upon the spring *g*, ready to be acted upon at the descent of the piston.

The piston *G* contains an amount of gravity together with its own weight, corresponding with its lifting power or buoyancy, by which, in its descent, it is made to reverse the action of the stop-cocks by a sudden motion, in precisely the same manner as described for its ascent, thus opening the exhaust and closing the force-pipe.

It is, of course, understood that the machine should be so constructed, that when the piston descends, it will, under no circumstances, come below the inducting and educting water-pipes.

The reason of the devices for checking the piston in its ascent and descent is, that the stop-cocks operated by its action require to be opened suddenly, as it is obvious that if otherwise worked, as soon as the cocks were opened to a limited extent, there would be force admitted sufficient to check the rise of the piston, but not enough to expel the water, so that the action of the engine would become neutralized, which difficulty is entirely obviated by the sudden action of the reserved or accumulated force of the piston, which can be so constructed, without in any manner injuring the action of the engine, that any desired amount of force required for this purpose can always be obtained.

From what has been said, it is obvious that to complete the combination, an air-condensing engine is required, which is connected with the hydraulic engine by the force-pipe or conduit *I*, which is of sufficient size to act as a reservoir, or to be supplied with force

from a reservoir, into which air is forced by the condensing-engine.

The air exhausted at the upward stroke of the engine may be utilized for ventilating the mine in which the hydraulic engine is placed.

As a conduit for transmitting force from the condensing-engine to the hydraulic engine, I intend to employ the means patented by me, October 5, 1869, (mode of transmitting power,) by which means the condensing-engine may be placed at any desired distance from the mine.

I do not confine myself to the exact construction or arrangement of the mechanism composing the engine herein described, as the principle embraced is susceptible of other embodiments or modifications, and yet employ substantially the invention which I desire secured by Letters Patent.

What I claim, therefore, is—

1. A pneumatic engine into which condensed air is admitted, and from which it escapes through alternating cocks, automatically operated, substantially as described.

2. A plurality of cocks, connected by a crank or cam-arrangement, and operated by the ascent and descent of the float-stem, substantially as described.

3. An engine constructed and arranged as described, so that it will work automatically for ejecting the water when a given quantity thereof shall be received into the engine, and by which means the power is admitted to expel the water, substantially as described.

In testimony that I claim the foregoing as my own, I affix my signature, in presence of two witnesses.

ROBERT SPEAR.
